United States Patent

Des. 241,579
Patented Sept. 21, 1976

241,579

NUMERICAL LOGOTYPE FONT

Ray J. Harris, 7627 Colehaven, Boise, Idaho 83704

Filed Aug. 8, 1974, Ser. No. 492,389

Term of patent 14 years

Int. Cl. D18—03

U.S. Cl. D64—12 B

The figure is a face view of a numerical logotype font showing my new design.

I claim:

The ornamental design for a numerical logotype font, substantially as shown.
